CARBON DIOXIDE ICE APPARATUS AND PROCESS

Original application filed December 6, 1926, Serial No. 152,754. Divided and this application filed December 15, 1928. Serial No. 326,274.

My present invention includes certain lumps of snow. These lumps consist of features set forth in my pending application Ser. No. 152,754, filed December 6, 1926, of which this is a division. It is related to the 5 invention set forth in a companion application, Ser. No. 153,064, now Patent No. 1,659,435, granted February 14, 1928, in that it concerns large quantity production of solidified carbon dioxide in the form of so-called carbon dioxide snow and compression thereof to form dense, structurally coherent blocks such as are now going into extensive 10 use for refrigeration and similar purposes.

As is well known, carbon dioxide cannot 15 exist as a liquid at atmospheric pressures, but the snow, when formed, is stable at atmospheric pressures and temperatures and can be handled as a commercial product although its evaporation temperature is approximate- 20 ly 110° below zero Fahrenheit. Upon melting, it simultaneously absorbs the latent heats both of liquefaction and boiling, thereby sublimating from solid directly to gas form, at atmospheric pressures.

25 The carbon dioxide snow is produced from carbon dioxide which is maintained in liquid form by subjecting it to critical temperature and pressure of liquefaction. The liquid is transformed to crystalline or snow form by 30 releasing the pressure to permit sudden gasification of the liquid and expansion of the resultant gas.

My present invention relates more particularly to means for compressing the snow 35 into blocks, preferably in an extension of the extremely cold snow forming chamber whereby loss of the carbon dioxide gas is minimized, and the snow is preserved in the cold atmosphere, insulated from heat until 40 after it has been compressed into blocks, in which form it is in relatively stable condition for extrusion into the open air for use as a finished commercial product.

I have discovered that the production of 45 blocks of dense, tough, structurally sound solid carbon dioxide cannot be accomplished merely by one direction pressure applied by a piston which constitutes one wall of a molding chamber. This is because of the gases 50 that are intimately bound in the pores of the

broken fragments of the deposit formed in the snow chamber and these deposits consist of crystals that are welded together so as to enclose great quantities of finely subdivided 55 CO₂ gas. In practice, it is found that the molding pressure expels very little of this gas. Consequently, the gas is highly compressed with and sealed in the snow and this results in a complete block that is under great 60 internal tension, making it structurally weak.

65 Preferably, such expulsion is accomplished by a tamping operation carried out by tamps or crushers that are of much less area than the snow surface against which they strike. 65 The action of the tamps on local areas of the snow mass expels the air and gases through the surface of the snow adjacent the tamps. This tamping also snugly compacts the mass 70 by breaking down the snow crystals and prepares it for the final compressing and molding operation which forms it into tough, hard blocks free of gas and air bubbles.

75 Preferably, the fragmentary masses of snow from the forming chamber fall into a bin of uniform cross-sectional area whereby I avoid the danger of wedging the snow in a tapered passageway. The snow, sustained against lateral expansion is tamped down by one or more relatively small, vertically reciprocated, gas-expelling tamps.

80 Subsequently, a cut-off blade or valve may be moved into position to segregate the tamped snow in the bottom of the bin from that descending from the snow chamber and 85 the previously tamped mass is subjected to the powerful lateral pressure of a molding piston in a direction transverse to the direction of tamping while sustained against expansion in other directions by the cut-off 90 and the walls of the bin.

95 Preferably, one formed block serves to sustain the thrust of the piston on the next block and the piston acts both to form and eject blocks.

The above and other features of my invention will be more evident from the following description in connection with the accompanying drawing, in which

Fig. 1 is a longitudinal vertical section. 100

through the lower or discharge end of a snow-forming chamber and its associated collecting bin; and

Fig. 2 is a vertical section on the line 5 2-2, Fig. 1.

Structurally considered, the snow making chamber fully described in the parent application above referred to, includes the inner metal casing 4, of conventional construction, supported in any desired way in an outer metal shell, 5, so as to leave an interspace 6, 6, 6, for circulation of the waste carbon dioxide gas which has an outlet through screen 7 near the discharge end of the chamber. This cold gas is directed primarily downward into the interspace 6a surrounding the collecting bin and compressor described hereafter, from whence it escapes or is exhausted in any suitable manner, not 10 shown.

The expansion nozzle, as also the precooling super-compression and follow-up pressure on the supply of the liquid to the nozzle, breaking up of the snow deposited on the 15 walls of the chamber, etc., may be as set forth and claimed in said companion applications.

The snow fragments and powder from the snow forming chamber fall into the space 20, which is a hopper for a compressor, comprising a tubular member, 21, which, as shown in Fig. 2, is rectangular in cross-section, extends transversely of the apparatus, is open at one end, 24, for exit of the compressed 25 product and is closed at the other end by head 22, reciprocated by a power cylinder, screw or other suitable motor means. Its normal retracted position as shown in full lines, Fig. 2, is just clearing the downward discharge opening of hopper 20. Above the piston is a 30 valve-like plate, 23, sliding in grooves 25, its forward edge being preferably beveled, as shown so as to cut through snow when the space 21 is over-filled. It remains in the closed position, cutting off escape of the snow and serves as a top wall for the compression 35 space when the piston 22 advances to the dotted line position shown in Fig. 2.

For compressing the first block, a plug or 40 other abutment must be used to sustain the pressure of the plunger against the snow, but thereafter the first block, α , may be pushed to the position α' so that each formed block affords a compression abutment for each succeeding block compressed by the plunger. I 45 prefer to provide inwardly projecting fingers such as 27 at intervals about the cavity, at a point registering with the rear surface of the second block. When in the projected position as shown in Fig. 2, they serve to sustain part of the thrust pressure of the piston, and they may be utilized to assist in maintaining separation of blocks α and α' .

The fingers 27 are withdrawn after the 50 block α has been compressed, to permit the

plunger to advance and force said block to the position α' , and thereby force the block α' onto the conveyor 28.

It is obvious that the slide, 23, may be advanced and the piston, 22, reciprocated several times to build up a block of desired thickness and density.

For the making of coherent blocks of uniform density, I find it highly desirable to employ some form of tamps, such as 30, 31, capable of reciprocating to the bottom of the mold box 21. These are reciprocated either by hand or preferably by machinery diagrammatically indicated at 32, to break up the lumps, release the gas therefrom and tamp 5 30 down the loose snow and fragments into a fairly uniform mass in the space in front of the plunger, before the plunger advances. When the snow is thus tamped, fewer reciprocations of the plunger are necessary to form 35 a block of desired size and density and the block will be free from compressed gas to an extent unattainable in any other way.

A one direction pressure against the block is in itself inoperative to expel gases since 40 there is no opportunity for the gas to escape. The tamping, however, by tamps of less area than the snow surface against which they impinge, effectively drives entrapped gas and air out through the top of the mass and presents a relatively gas free compact mass of 45 snow to the piston for the final molding operation.

From the above, it will be seen that the apparatus is adapted for efficient snow packing, compressing and ejecting, all in a region near the freezing point of the carbon dioxide, so that there is little waste by melting. During the process and after the block is ejected, it is dense enough to permit a reasonable time 50 for transit through the open air to a place of storage without appreciable loss. Furthermore, the various steps of the process are continuously progressing and uninterrupted, so that with apparatus of the capacity above mentioned it will be possible to turn out many 55 tons of commercial carbon dioxide blocks per twenty-four hours.

I have discovered that if sufficient pressure be applied, the snow can be fused or rather 60 welded by the heat of compression, into very dense, tough blocks of solid carbon dioxide that are of much greater specific gravity than water, say 85 lbs. to 95 lbs. per cubic foot or even more. Such blocks are in many respects the same as similar blocks of the same density which can be made by direct freezing of liquid under high follow-up pressure, but my way of making such blocks has 65 certain advantages under some commercial 70 conditions often encountered in practice.

I claim:

1. Means for supplying carbon dioxide snow, a mold into which said snow discharges, a reciprocatory plunger in the mold 75

and a cut off between said carbon dioxide snow supplying means and said mold for closing the mold entrance opening and forming when closed a lateral wall of the mold during the compression stroke of the plunger.

5 2. Means for supplying carbon dioxide snow, a mold into which said snow discharges, a reciprocatory plunger in the mold, means for tamping the snow in the mold while the plunger is retracted, and a cut off for closing the mold entrance opening during the compression stroke of the plunger.

10 3. Means for supplying carbon dioxide snow, an open ended mold into which said snow discharges, said mold having one end closed by a retracted reciprocatory plunger and the other end by a previously compressed block of the snow whereby pressure of the said plunger compresses the intermediate snow and then ejects said previously compressed block, means for tamping the snow in the mold while the plunger is retracted, and a cut off for closing the mold entrance during the compression stroke of the plunger.

15 4. The method of making dense masses of solid carbon dioxide, which includes expanding liquid carbon dioxide to make snow and, while excluding air, partially compacting the snow into a mold and then compressing the snow in a direction different from that of the compacting.

20 5. The method of making dense masses of solid carbon dioxide, which includes expanding liquid carbon dioxide to make snow and, while excluding air, tamping the snow to expel carbon dioxide gas and then compressing the snow.

25 6. The method of making dense masses of solid carbon dioxide, which includes expanding liquid carbon dioxide to make snow and, while excluding air, tamping the snow to expel carbon dioxide gas and then compressing the snow transversely to the direction of tamping.

30 7. The method of making dense masses of solid carbon dioxide, which includes expanding liquid carbon dioxide to make snow and, while excluding air, compacting the snow in a mold and then compressing it to a desired higher density by pressure applied transversely to the direction of compacting.

35 8. The method of making dense masses of solid carbon dioxide, which includes expanding liquid carbon dioxide to make snow, breaking up the deposited snow, compacting it in one direction and then compressing it transversely to the direction of compacting.

40 9. A method of forming a block of dense structurally sound solid carbon dioxide which includes tamping a mass of carbon dioxide snow to expel the gases therefrom.

45 10. A method of forming a block of dense structurally sound solid carbon dioxide which includes tamping a mass of carbon dioxide snow to expel the gases therefrom and subse-

quently compressing the tamped snow in direction transverse to the direction of tamping.

Signed at New York, in the county of New York, and State of New York, this 14th day of December, A. D. 1928.
